US00D850532S

(12) **United States Design Patent** (10) Patent No.: **US D850,532 S**
Lee et al. (45) Date of Patent: ** Jun. 4, 2019

(54) **DIGITAL SIGNAGE**

(71) Applicant: **LG ELECTRONICS INC.**, Seoul (KR)

(72) Inventors: **Yoonkyeong Lee**, Seoul (KR); **Yongho Lee**, Seoul (KR)

(73) Assignee: **LG ELECTRONICS INC.**, Seoul (KR)

(**) Term: **15 Years**

(21) Appl. No.: **35/504,815**

(22) Filed: **Oct. 23, 2017**

(80) **Hague Agreement Data**

Int. Filing Date: **Oct. 23, 2017**

Int. Reg. No.: **DM/098261**

Int. Reg. Date: **Oct. 23, 2017**

Int. Reg. Pub. Date: **Apr. 27, 2018**

(30) **Foreign Application Priority Data**

Apr. 24, 2017 (KR) 30-2017-0018978

(51) LOC (11) Cl. **20-02**

(52) U.S. Cl.

USPC **D20/41**
